UNITED STATES PATENT OFFICE.

EDWIN S. FLARSHEIM, OF CINCINNATI, OHIO, ASSIGNOR OF ONE-HALF TO JOHN G. H. LIEBEL, OF CINCINNATI, OHIO.

TIME SWITCH.

Application filed March 23, 1925. Serial No. 17,484.

My invention relates to a time switch for opening and closing the contacts of an electric circuit, the invention being in the nature of an improvement and simplification of the 5 device broadly disclosed and claimed in co-pending application Serial No. 506,612, filed October 10, 1921.

The object of the present invention is to 10 improve upon the push plunger structure and operation and the mechanism for automatically tripping the plunger to open the contacts at the end of a predetermined period of contact closing.

The invention has particular value when 15 used to control the circuit of an X-ray machine, although its utility is not confined to any specific usage.

In X-ray machines it is particularly desirable to be able to take a perfectly definite 20 time exposure even to the fraction of a second. It is also desirable to be able upon occasion to open the contacts before the expiration of the time period. It is also desirable to provide a switch which can be 25 manually operated independently of the time mechanism. It is also desirable to have the full force of the clock spring utilized in the tripping operation which opens the contacts.

30 The features of the invention are more fully set forth in the description of the accompanying drawings forming a part of this specification, in which:

Figure 1 is a rear view of the switch with 35 the cover removed.

Figure 2 is a sectional view taken on line 2-2, of Fig. 1.

Figure 3 is a sectional view taken on line 3-3, of Fig. 2, showing the tripping mechanism in normal non-operative position.

Figure 4 is a sectional view taken on line 4-4 of Fig. 1.

Figure 5 is a view taken the same as Fig. 3 and showing the tripping mechanism in 45 the act of moving the plunger to disengage the switch contacts.

Figure 6 is a fragmentary face view of the switch with certain parts removed.

Figure 7 is a face view of the dial.

50 Figure 8 is a detail view of the cam ring for tripping the mechanism.

Figure 9 is a sectional view of the clock mechanism.

Figure 10 is a sectional view taken on line 10-10, of Fig. 2.

The exact form and arrangement of the parts comprising the mechanism in relation to one another and the exact form of the casing for disposing of the parts may be variously modified, depending upon the 60 usage and position the time switch unit is to have in relation to the electric device which it is to control.

For the purposes of an X-ray time switch unit best adapted to illustrate the principle 65 of the invention, I preferably use a tubular casing 1 in which the plunger and contact mechanism is supported in axial relation to the casing; there being preferably a lateral tubular extension casing portion 2 at the upper end for housing the clock mechanism.

Throughout the specification and claims 70 for the purposes of brevity and clarity, I have referred to the power source or motor train as a clock mechanism, it being understood that any other form of device capable of storing up or delivering energy to be released and stopped after a predetermined time operation is broadly equivalent.

The contacts 3, 4, of the copper spring 80 blade type, and the spring blade actuator 5 therefor with the insulating block 6, preferably formed with the deflected portion 7, are mounted in parallelism in the supporting block 8 upon the inside of the casing, 85 the lower projecting ends of the contacts being connected with the electric conduits 9 which are led through an orifice at the bottom of the tubular casing. The actuator 6 is not absolutely essential, it being obvious 90 that the plunger could directly engage one of the contact blades if desired. The bracket 10 projected from the casing, positions and spaces the upper ends of these three blades below the insulation block 6, but this 95 member may be omitted if desired.

The plunger in the present instance is preferably a flat or rigid blade-like or plate-like piece of metal which can conveniently be formed as a stamping and this plunger 100 blade 11 preferably has its upper end formed with or connected to a push button 12 upon the top of the tubular casing and seated in an annular recess 13.

This plunger member is supported in a 105 manner permitting the plunger to have a

spring controlled reciprocal longitudinal movement in the casing for manually opening and closing the contacts and it must be also so supported that it may have, when in 5 depressed position, a second, or relatively independent, but preferably a lateral movement for effecting the automatic disengagement or opening of the contacts. To enable these movements the upper end of the 10 plunger is formed with a central longitudinal guide slot 14 for a slide operation in relation to the headed pivot bolt 15 screwed into the casing, it being perfectly clear that this slotted pivotal form of support enables 15 a longitudinal movement of the plunger in relation to the pivot and also a pivotal action on said bolt when the plunger is depressed, enabling the lower end of the piston to make the swinging movement 20 by which the contacts are to be automatically disengaged. The upper end of the plunger adjacent the slot is preferably held against a bearing plate 16.

The lower portion of the plunger slides in 25 a guideway formed by a rib 17 of the casing and the cross bar 18 confining the plunger plate to a longitudinal reciprocal movement in one direction but permitting a lateral or pivotal movement of 30 the lower end of the plunger in the plane of the guideway.

This plunger is positioned to reciprocate in a central portion of the tube casing for compactness of structure and it is positioned 35 between the contact springs and their actuator on one side and the clock mechanism on the other side. To this end the plunger plate which is to directly operate the contacts upon one side and also to directly operate 40 the clock releasing mechanism and to be tripped by the clock member upon the other side of the plate, is formed with a projection on one side for operating the contacts, and a projection also on the other side, to 45 operate in relation to the clock mechanism. In the thin, blade-form of plunger, which we preferably employ, these two actuating plunger members or projections may be conveniently formed by cutting out a medial 50 portion of the plunger and bending outwardly a tongue 19 constituting a detent to engage the deflected end 7 of the contact actuator 6 so that when the plunger is depressed this tongue 19 engages the deflected 55 end 7 and closes the contacts. When the plunger is moved laterally by the time-trip, the tongue 19 has a trigger-like escapement from the part 7.

When the plunger is released it moves 60 away from this engagement opening the contacts. On the other side of the plunger is a projection or dog 20 constituting the member to be tripped and also constituting a member to operate the clock releasing 65 mechanism.

This blade plunger is held in the normal position shown in Fig. 1 by means of the coil spring 21 which holds the plunger normally in its raised or open contact position and also holds it normally in its central vertical position, so that the spring 21 operates to return the plunger either when released from depressed position or when laterally moved for breaking the contact by the automatic tripping action. 75

At the end of the tripping movement the tripping member is engaged against the side or edge of the plunger member to be tripped, the plunger being swung to one side of its normal position. In order to permit the plunger to return to normal position, I preferably provide the notch 22 upon the lower end of member 20, permitting a trigger-like escapement enabling the member 20 to move past and over the tripping member when the depressed plunger is released and automatically return to its normal position. 80 85

It will be seen from the disclosure so far, that the plunger may be manually reciprocated at any time independently of the clock mechanism so that the opening and closing 90 of the contacts is always under optional manual control.

The clock mechanism will be later described in generality, but for the present purpose it is sufficient to say that the power shaft 40 has a setting knob 23 on the dial face 24 (see Fig. 7). On the other end of shaft 40 is fixed the crank arm 25 having the laterally extended finger 26, said crank arm and its lateral extension constituting the tripping member which moves in the arc of a circle when the power shaft is driven by the clockworks it being understood that the indexed portion of the arc of the circle represents a corresponding time period of operation. This power shaft, as will best be seen in Fig. 2, is substantially adjacent the plunger member 20 to be tripped so that when the plunger is depressed to close the contacts this member 20 will be interposed in the path of movement of the finger 26. When this clock-operated tripping member 25, 26 rotates in the arc 105 of a circle so that the arm 26 strikes the side of the plunger member 20 to be tripped, the plunger has a relatively lateral movement in its bearings and in relation to its pivotal support, which disengages the plunger member 19 from the deflected end 7 of the contact actuator 6. That is to say, when the plunger is moved laterally by the tripping action of the clock mechanism the plunger member 19, disengages member 7 110 and the contacts are broken. 115 120

On the back plate of the clock within the casing is a bell crank lever 27 engaging with a latch 28 holding the clock normally locked against operation, the bell crank lever being normalized in this position by a 130

spring 29. The lower end of the bell crank lever 27 has a stirrup extension 31 in the direction of the plunger, and this stirrup occupies a position below the crank arm 26 of the tripping member.

Looking at Figs. 7 and 6, it will be seen that the indicating clock hand 32 on shaft 40, is pointing to the arrow shown on a portion of the dial not indexed. The dial index numbers the seconds or fractions from zero point on in a direction clock-wise. On the inner end of shaft 40 is a pawl arm 33 carrying a spring pawl 34 for operating the ratchet wheel 35 loose on shaft 40, so that the clock hand 32, shaft 40 and pawl arm 33, may operate as a unit in the counter-clockwise direction. Abutting the front plate of the clock is a cam ring 36 formed with a shoulder or stop 36^a for engaging the outer end of the arm 33 to stop the clock definitely when the spring is run down and the clock hand 32 is pointing to the arrow, that is, in an un-indexed position. The arm 33 when operated by clock spring moves counter-clockwise and the pawl 34 is tripped by a cam 37 adjacent the stop 36^a so that the pawl is released from engagement with the ratchet wheel when the clock hand 32 is moved from the zero point to the arrow point in a counter-clockwise direction. It will thus be seen that when the clock hand 32 or indicator is unset for a timed operation the plunger may be freely reciprocated without effecting the clock releasing, but when the clock hand 32 is set, say to point 4 on the dial, for a corresponding time operation the pawl arm 33 has moved away from stop 36^a so that the clock movement isn't arrested, which movement of the clock hand winds the clock spring, so that when the clock hand 32 is thus set and the clock spring wound, the depression of the plunger moves the bell crank on its fulcrum to the clock releasing position shown in Fig. 5, and this depression of the plunger, as before stated, places the plunger member 20 which is to be tripped in the path of travel of the clock-operated tripping finger 26.

The details of the clock mechanism are not new in themselves and need not be detailed, inasmuch as Fig. 10 shows the ordinary escapement mechanism in plan in a manner which will be understood clearly by those skilled in the art.

Figure 9 shows a central vertical section through the elements mounted on the power shaft.

All the elements in this figure are fixed in relation to the power shaft 40, except the ratchet wheel 35 and the time train gear 41 which are unitarily mounted loosely thereon, but which members 35, 41, become fixed to rotate with its shaft 40 in its counter-clockwise direction.

By the mechanism and arrangement here-

in shown is made possible an operation whereby a plunger through a reciprocal motion and a lateral pivotal motion may directly operate the contacts and may directly operate the clock releasing mechanism, and may directly be tripped by the clock-operated tripping mechanism. This produces a very speedy operation without the lost motion which is incident to either compound type of plunger or to plungers which operate in relation to corresponding mechanisms through intermediary lever or transmission connections.

It is also highly advantageous, as fully disclosed and claimed in the previous case, that the whole force of the clock power is utilized in the kick-off or contact break when the clock hand moves counter-clockwise from the zero point to its normal position at the arrow. That is to say, the contacts are closed for the exact period definitely timed, while instantaneously, at the conclusion of that timed period, the full force of the spring comes into play at the moment of the tripping action, during the slight remaining motion of the hand to position in which it becomes definitely stopped in its counter-clockwise direction of travel.

Through this invention I am enabled to produce a single or one-piece plunger which in itself will engage the contacts, and at the same time release the clock mechanism.

Having described my invention, I claim:

1. In an electric time switch, in combination with the contacts, a clock mechanism, a clock-releasing and a clock-stopping mechanism, a one-piece, spring-normalized plunger positioned between said actuator and said clock mechanism, supporting means for said plunger enabling a manual reciprocal movement to operate the contacts and to operate the clock-releasing mechanism, said means permitting a relatively lateral movement of the plunger, a member on one face of the plunger to longitudinally engage and disengage the contacts and to laterally disengage said actuator, a member to be tripped on the opposite face of the plunger, a clock-operated tripping member adapted to be set for a timed operated engagement with said member to be tripped, and means for limiting the clock operated movement of said tripping member.

2. In a time switch, in combination with electric contacts, a clock mechanism, releasing mechanism therefor, a clock-operated tripping member adapted to be set for a timed movement to a stopping position, a longitudinally reciprocal and laterally movable spring-normalized plunger element formed and positioned for engaging and disengaging the contacts when the plunger is manually reciprocated and for automatically disengaging the contacts when the plunger is moved laterally, and a plunger member to be

tripped formed in a position to actuate the clock release when the plunger is reciprocated and to be automatically actuated by said tripping member to effect the lateral plunger movement.

3. In a time switch, a casing, a plate-like member constituting a plunger element, pivotal slot and guide connections between said plate and the casing enabling said plunger to have a longitudinal movement and a relatively lateral movement in the plane of the plate when the plunger is depressed, a clock actuated tripping member adapted to be moved from a stopped position for a timed operation, a clock releasing means and contacts, the clock mechanism and contacts being adapted to be coordinate- 10 ly operated by the longitudinal and lateral movements respectively of said plunger, and a spring for normalizing said plunger plate.

4. In a time switch, a casing, a plate-like plunger member, a normalizing spring there- 15 for, pivotal slot and guide connections between the casing and plate, enabling a longitudinal movement of the plate and a lateral

movement of its lower end when depressed, a clock-actuated tripping member adapted to be moved from a stopped position for a timed operation, a clock-releasing mechanism, contacts and actuator, a member on one face of the plate for longitudinally engaging and operating said actuator in the lateral movement of the plunger, said member having a trigger-like escapement from the actuator in the lateral plunger movement, a member on the other face of the plunger plate adapted to actuate said clock-releasing mechanism and also adapted to be actuated by said tripping member to move the plunger laterally, and means constituting a trigger- 30 like escapement of the tripping member with the member to be tripped when the plunger has been swung to its contact disengaging position, enabling the tripping member to complete its movement to the normal or 35 stopped position.

In witness whereof, I hereunto subscribe my name.

EDWIN S. FLARSHEIM.
